[57] CLAIM

The ornamental design for a design of a container with a toggle clasp, as shown and described.

DESCRIPTION

FIG. 1 is a perspective view of a container with a toggle clasp showing our new design; shown in an open position with toggle clasp open; and,

FIG. 2 is a second embodiment of FIG. 1; shown in an open position with toggle clasp open.

The undisclosed opposite sides are identical to the corresponding disclosed sides. The top and bottom of both embodiments are plain and unornamented.
